US00D991238S

(12) **United States Design Patent** (10) **Patent No.:** **US D991,238 S**
(45) **Date of Patent:** **** Jul. 4, 2023**

(54) **CASE FOR ELECTRONIC
COMMUNICATIONS DEVICE**

(71) Applicant: **SPIGEN KOREA CO., LTD.**, Seoul (KR)

(72) Inventor: **Seungjoo Kim**, Seoul (KR)

(73) Assignee: **SPIGEN KOREA CO., LTD.**, Seoul (KR)

(**) Term: **15 Years**

(21) Appl. No.: **29/788,166**

(22) Filed: **Apr. 1, 2021**

(51) **LOC (14) Cl.** **14-03**

(52) **U.S. Cl.**

USPC **D14/250**

CLAIM

The ornamental design for a case for electronic communications device, as shown and described.

DESCRIPTION

FIG. 1 is a front perspective view of the case for electronic communications device showing my new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the drawing figures form no part of the claimed design and depict portions of the case for electronic communications device that form no part of the claimed design.

1 Claim, 8 Drawing Sheets
